UNITED STATES PATENT OFFICE.

SERGIUS P. GRACE, OF PITTSBURGH, PENNSYLVANIA.

TELEPHONE-RECEIVER.

1,035,577.

Specification of Letters Patent. Patented Aug. 13, 1912.

Application filed October 17, 1910. Serial No. 587,388.

To all whom it may concern:

Be it known that I, SERGIUS P. GRACE, a citizen of the United States, residing at Pittsburgh, in the State of Pennsylvania, have invented a new and useful Improvement in Telephone-receivers, of which the following is a full, clear, concise, and exact description.

My invention relates to telephone receivers and has for its object to magnify the available energy in a telephone line.

The structure of my invention comprises as its principal elements a magnet, a winding therefor adapted to receive varying currents, an armature and a metallic disk, the disk being rotated at high speed in proximity to the armature so as to induce therein Foucault or eddy currents and the armature being connected to a device such as a diaphragm for causing the movements of the armature under the influence of the magnet to create sound waves.

My invention also consists in the method of magnifying the available energy in a telephone circuit by rotating a metallic disk at high speed in proximity to the armature of an electromagnet and varying the magnetic force in the armature by means of varying currents in the coil of the magnet.

My invention will be better understood by reference to the accompanying drawing, in which—

Figure 1 is a side elevation of the structural arrangement of my telephone receiver; Fig. 2 is a front elevation of the same with the diaphragm, its containing cup and horn removed.

Like reference characters indicate like parts in the two figures.

The magnetic mechanism comprises a U-shaped permanent magnet 1, having soft iron pole pieces 2, 3, surrounded by coils 4, 5, serially connected in a telephone circuit indicated by the conductors 6. Mounted on a pivot pin 7 extending through the free ends of the soft iron pole pieces 2, 3 is a member comprising two parts 8, 9 which converge at their lower ends and embrace the outer edge of a metallic disk 10. This disk is represented as being mounted upon the shaft of a motor 11 so as to be rotated at high speed. The upper ends of the two parts 8, 9 are joined by a non-magnetic pin 12, to the central part of which is attached a connecting arm 13 which is fastened at its

outer end to a diaphragm 14. This diaphragm is suitably supported in a flanged cup 15 provided with a horn 16.

The operation of my telephone receiver is as follows: The permanent magnet 1 creates a magnetic circuit by way of the pole pieces 2, 3, the parts 8, 9 and the gap, and through the outer edge of the portion of the disk 10 between the converging lower ends of the parts 8 and 9. The disk being rotated at high speed, Foucault or eddy currents are generated therein and react on the armature to create a normal pull or torque on the parts 8 and 9. The velocity of the disk is uniform so that the torque on the parts 8 and 9 is constant so long as the strength of the magnetic circuit remains unchanged. When, however, the magnetic circuit is varied, as by telephonic currents in the coils 4, 5, the torque created by the rotating disk on the parts 8 and 9 is varied accordingly. Therefore the pressure on the diaphragm 14 through the connecting rod 13 is caused to vary in accordance with the varying current in said coils, and if such current is that caused by speaking into a telephone transmitter, the speech will be reproduced by the diaphragm.

It will be readily seen that by reason of the powerful effect which may be produced by the action of the rotating disk, the available energy in the telephone circuit 6 is greatly increased or magnified.

It is characteristic of my improvement that as the movement of the motor driven part or element is transmitted to the diaphragm or other movable part, by movable portions or extensions of the pole pieces of the electromagnets, which portions or extensions can be made very light, there will be little or no inertia to be overcome and the response of the diaphragm or other movable part to variations in the magnetic flux will be full and prompt. It is preferred that the movable portions or extensions of the pole pieces should be made in the form of a lever having its pivotal connection to the pole pieces intermediate the point of connection to the diaphragm and the point at which the energy of the motor driven member is applied. By properly arranging the pivotal point of the lever relative to the points of connection to the diaphragm and of applied energy, the amplitude of the original vibrations can be increased or di-

minished, or if the electric current is feeble its effects in the diaphragm can be increased.

It is to be understood that my invention is not limited to a structure in which the 5 rotating disk acts upon a diaphragm to produce sound waves in the air. I may, for example, connect the parts 8 and 9 to a transmitting telephone which, in turn, would be connected in a circuit leading to 10 receiving telephones at a distant point. When used in this way my telephone receiver becomes a powerful telephone repeater.

Having thus described my invention, what 15 I claim and desire to secure by Letters Patent is:

1. In a telephone receiver, the combination of a stationary electromagnet having pole pieces movable to the legs of the magnet, 20 a metallic element movable in proximity to said pole pieces, and a movable part or element adapted to be shifted by the pole pieces.

2. In a telephone receiver, the combination of an electromagnet having portions movable relative thereto, a metallic element movable in proximity to said portions of the pole pieces, and a movable part or element adapted to be shifted by the movable 25 portions of the pole pieces.

3. In a telephone receiver, the combination of an electromagnet, a lever pivotally mounted on and forming the pole pieces of said magnet, a motor driven metallic 30 part or element arranged in proximity to

said lever, and a part or element adapted to be shifted by said lever.

4. In a telephone receiver, the combination of an electromagnet, a lever pivotally mounted on and forming the pole pieces of 40 said magnet, a metallic disk rotating in proximity to said lever, and a movable part or element adapted to be shifted by the lever.

5. In a telephone receiver, the combination with an electromagnet, a movable member comprising two parts mounted in proximity to the two poles respectively of said electromagnet, and a metallic disk rotating between the parts of said member. 45

6. In a telephone receiver, the combination with an electromagnet having two poles, of a member comprising two parts, one for each pole, pivoted so as to be movable relative to said poles, and a metallic disk rotating between the parts of said armature. 50

7. In a telephone receiver, the combination with an electromagnet having two poles, of a member having two parts pivoted so as to move relative to the said poles, a metallic 55 disk rotating between the parts of said member, a diaphragm and a connection between said member and said diaphragm.

In witness whereof, I hereunto subscribe my name this 28th day of September, A. D. 65 1910.

SERGIUS P. GRACE.
